UNITED STATES PATENT OFFICE.

ZENSAKU ISHIWATA, OF LOS ANGELES, CALIFORNIA.

HAT-RETAINING DEVICE.

Application filed September 2, 1925. Serial No. 54,067.

The present invention relates to an improved device for keeping the hat in position upon the head to prevent the wind from blowing the hat off.

5 The object of the invention is to provide a device of this character, which may be manufactured cheaply, or inexpensively, to provide a hat securing device which may be applied for use to any hat, which may be
10 drawn in beneath the sweat band of the hat when not in use, or detached from the hat, and to provide a securing device which is inconspicuous in use, and to provide a device for retaining the hat, which may be
15 quickly drawn from beneath the sweat band when it is desired to use the same.

To accomplish the objects of the invention, I provide eyelets adapted to be secured to and inserted in the sweat band of the hat
20 and on either side thereof, cords formed into a loop to engage with the ear on either side of the hat, means for adjusting the cords for use, and a ring attached to the loop whereby the same may be quickly drawn
25 from beneath the sweat band for use.

While the drawings illustrate a preferred form of the invention, it will be evident to those skilled in the art, that my invention permits of various modifications without departing from the spirit thereof, or the scope of the appended claims.

In the drawings, Figure 1 is a perspective view of my improved hat retaining device. Fig. 2 is a sectional and perspective view of
35 a hat having my device applied thereto.

Referring to the drawings, the device consists of an elastic cord member 11, formed into a loop, and having on one end a metal eyelet 12, to which the free end of the cord
40 11, is tied to form the loop and to adjust the same to the ear of the user. The cord loop is passed through eyelet 13, which is adapted to be secured to the sweat band 14, of the hat. The eyelet member 12, prevents
45 the cord loop from being drawn through the eyelet 13, when in use, and remains concealed beneath the sweat band. The adjusting ring 15, is attached to the loop on the outside of the sweat band, and affords a means for
50 quickly drawing the device outward for use.

In use, the device is first applied to the sweat band of the hat in the manner above set forth. The loop is drawn out and is passed under the ear of the user. The hat is
55 equipped with a retaining device, one on either side of the hat.

From the foregoing description taken in connection with the drawings, it may be seen that I have provided a simple and efficient device for retaining the hat upon the head
60 of the user, when the wind is blowing. By the use of this device the hat is retained in position, and is especially advantageous while the user is riding on a car or steamship or in an automobile.

When not in use, the device may be drawn inwardly and will lie beneath the sweat band, and will be concealed thereby. The eyelet 12, and ring 15, serve to prevent the device from being detached from the hat
70 and lost, the ring 15, being provided with a bar 16, which cannot pass through the eyelet 13, and which will remain close to the sweat band when the device is not in use.

What is claimed is:

1. In a hat retaining device, the combination with an eyelet adapted to be secured to the sweat band of the hat and adjacent to the ear of the user, of a cord loop including an external portion passed through said eyelet, 80 an eyelet member on the inner end of said loop, and normally lying beneath the sweat band, said external portion of said loop engaging with the ear of the user, a ring attached to the cord loop and exteriorly with
85 reference to the sweat band, and a bar integral with the ring.

2. In a hat retaining device, the combination with a cord loop adapted to engage with the ear of the user, of an eyelet adapted to be secured to the sweat band, said loop passing through the eyelet in the sweat band, means for preventing the loop from being detached from the eyelet in the sweat band consisting of an adjusting eyelet inside of
90 the sweat band, and a ring secured to the loop on the exterior of the sweat band, and a bar integral with the ring.

3. In a hat retaining device, the combination with an eyelet adapted to be secured to the sweat band adjacent to the ear of the user, an elastic cord loop passing through the eyelet in the band, means for adjusting the loop to the ear, and means on the outer and inner ends of the loop, serving to prevent detachment of the device from the eyelet in the sweat band.

In testimony whereof, I hereunto affix my signature.

ZENSAKU ISHIWATA.
